UNITED STATES PATENT OFFICE

RAYMOND L. PLUMLEY, OF BROOKLYN, NEW YORK, ASSIGNOR TO FREDERICK OSANN COMPANY, OF NEW YORK, N. Y., A CORPORATION OF NEW YORK

DESIGN FOR A PORTABLE SEWING-MACHINE FRAME

Application filed April 10, 1928. Serial No. 26,215. Term of patent 14 years.

To all whom it may concern:

Be it known that I, RAYMOND L. PLUMLEY, a citizen of the United States, residing at Brooklyn, New York, in the county of Kings and State of New York, have invented a new, original, and ornamental Design for a Portable Sewing-Machine Frame, of which the following is a specification, reference be-

ing had to the accompanying drawing, forming part thereof.

Figs. 1 and 2 are elevations in perspective from opposite sides of the machine frame.

I claim:

The ornamental design for a portable sewing machine frame, substantially as shown.

RAYMOND L. PLUMLEY.
